(57) **CLAIM**

The ornamental design for a container for volatilizing chemicals, as shown and described.

DESCRIPTION

FIG. 1 is a perspective view of the front, top and right side of a container for volatilizing chemicals showing our new design;

FIG. 2 is a rear view thereof;

FIG. 3 is a right side view thereof;

FIG. 4 is a top plan view thereof;

FIG. 5 is a bottom plan view thereof;

FIG. 6 is a cross sectional view of A—A of FIG. 4 thereof;

FIG. 7 is a front plan view thereof;

FIG. 8 is a left side view thereof;

FIG. 9 is a C—C end view of FIG. 7 thereof; and,

FIG. 10 is a B—B end view of FIG. 7 thereof.

The portions of the article in broken lines are shown for illustrative purposes only and form no part of the claimed design.
